UNITED STATES PATENT OFFICE.

JOSEF SCHIESSLER, OF BADEN, NEAR VIENNA, AUSTRIA-HUNGARY.

TELEPHONIC AND TELEGRAPHIC APPARATUS.

1,109,472.

Specification of Letters Patent. Patented Sept. 1, 1914.

Application filed August 18, 1908. Serial No. 449,345.

To all whom it may concern:

Be it known that I, Dr. JOSEF SCHIESSLER, subject of the Emperor of Austria-Hungary, residing at Baden, near Vienna, Austria-Hungary, have invented certain new and useful Improvements in Telephonic and Telegraphic Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The problem of the telephone relay has occupied the attention of those interested in the industry for many years without its having been up to now practically solved. All the solutions which have been tried the applicant considers suffer from the mistake that the transmissions of minute variations of current in one circuit to another having a stronger continuous current, were attempted in an antiquated manner. Most commonly contact transmissions, that is to say, mechanical devices were employed; inductive transformation from a weak to a strong current is seldom used in a telephone relay. Even in this case also, no important results were obtained, although the method is decidedly better than transmission by contacts, and purer transmissions are obtained.

Now this invention attempts to transfer to the domain of telephony with wires, experiences acquired by the applicant in the domain of wireless telegraphy and telephony. The most important factor is the experience resulting in the knowledge that small variations, such as talking alternating currents, Morse key interruptions, etc., can scarcely be strengthened at all in one and the same circuit. Pupin's arrangement which inserts a self-induction coil in a long conductor at distances of two kilometers apart for the purpose of eliminating injurious capacity, effects no real strengthening, but only an elimination of evils, and moreover opinions as to the success thereof are divided. It is more advantageous under all circumstances to employ a second and stronger circuit in such way that it acts in the manner of a relay. Experiments in this direction, partly with a view to another object and partly also relating to the production of a telephone relay, were first made by Duddell in

1900, (British Patent No. 21629 of 1900), and somewhat later by Gatti, (British Patent No. 1414 of 1904). In Duddell's case, however, the main object in view was to transform continuous electric current into alternating electric current and to produce oscillations of high frequency, without contemplating any special application for the latter other than that of wireless telegraphy, as far as can be gathered from the said specification. He made use for his purpose of a negative resistance in conjunction with the Thomson oscillating circuit. Duddell's negative resistance was also used by Gatti. In Gatti's case, however, the Thomson (or Duddell) oscillating circuit was dispensed with in the logical working out of the original idea as first embodied in the United States Patent No. 684506 of March 12th, 1900, which shows the typical form of the transformer. As Gatti does not make use of an oscillating circuit the transmission to the secondary line is not effected by superposition of oscillations of high frequency, but by transformed alternating currents reinforced in a continuous current circuit of a special kind and which correspond to the original speech vibrations. Experiments, which I have made in this direction have shown that the resistance in such circuits plays the principal part, and it need not always be a purely metallic resistance, but under some circumstances it may be a non-metallic resistance, or, as is preferred, a resistance composed of metals and non-metals. The quicker one component alters its conductivity and therewith its resistance, the greater is the fall of the tension and the greater the amplitude of the current fluctuation.

Only such relay resistances are used for the purposes of this invention as are applicable to a wide range of conditions, that is to say, such in which on small fluctuations of ohmic resistance large variations of voltage are produced, and vice versa. This is the case in all incandescent resistances, it being immaterial whether they are resistances having a negative temperature coefficient, as in Duddell's system, that is to say such in which the resistance decreases with increase in temperature, or whether they are resistances having a positive temperature coefficient, that is to say such in which with an increase in temperature the resistance also increases. The reason for this is as

follows: When a resistance is heated by the current, the heat thus generated is given off to the surroundings either by conduction or radiation. Each fluctuation in current will accordingly be attended by fluctuations in temperature, that is to say, fluctuations in the conduction and radiation of the heat. Conversely, each fluctuation in the conduction or the radiation of heat will be attended by current fluctuations. These current fluctuations are proportional to the square roots of the differences in temperature when it is a question of the conduction of heat, but where there is only radiation the current fluctuations are approximately proportional to the cube roots of the fluctuations in the radiation. As, however, conduction and radiation of heat are fairly variable quantities, it follows that by suitably influencing the same, considerable fluctuations in current can also be obtained. According to the specific nature of the incandescent resistance either the conduction of heat or the radiation of heat or both, or the magnetic field of the incandescent body may be influenced. In some cases all three effects will be applied. For the purposes of the present invention incandescent lamps and Tyndall platinum lamps are preferably used, without other incandescent lamps being excluded on that account. Now if an incandescent lamp with a spirally-wound incandescent filament be employed as a relay resistance, heat is given off from the incandescent filament by conduction and radiation. The conduction of the heat can but slightly be influenced, owing to the vacuum, but the reverse is the case with the radiation of heat, which, moreover, becomes more and more considerable at high temperatures. To this radiation the vacuum offers no resistance, but a partial resistance is offered by the glass wall, which only lets through the minor portion of the radiated heat (about 40%). The greater part of the radiated heat is reflected by the inner wall of the glass bulb and raises the temperature of the incandescent filament. Now this portion of the radiation can be influenced in the following way: By means of the solenoid-like winding of the incandescent filament a magnetic field is created which is both influenced in its lines of force by the magnetic field of the solenoid-like wound leads, or an electro-magnet may be included in the circuit, and, owing to the elasticity of the filament it is either caused to approach or recede from the wall of the incandescent lamp, which wall is more or less impervious to the heat rays according to its composition, thereby either increasing or checking the radiation, so that by this means the temperature of individual places in the filament and consequently also the strength of current in the same is varied. This result, however, can

be obtained not only with Duddell's so-called "negative resistances," but also with any positive or metallic resistance of suitable form, for example, an incandescent platinum spiral in either a non-exhausted or exhausted glass globe. The main object of the glass globe is to exclude undesirable air currents and their action. The incandescent lamp also contains a so-called "negative resistance;" nevertheless, neither Duddell nor any one else has hitherto succeeded in forming a "Duddell circuit" with it in just the same way as with a luminous arc. This is due to the vacuum in such lamp, which renders it impossible to directly influence the incandescent filament by heat absorbing means, such as air, hydrogen, etc. It is possible, however, to employ the incandescent lamp in the Duddell circuit in spite of its vacuum, by influencing its radiation of heat or its magnetic field, either as hereinbefore set forth, or in any other way. The effect may, however, be still further augmented, for example, by surrounding the incandescent lamp, or only the filament, with a smooth, non-magnetic metal lining impervious to the radiation of heat, for instance, by silvering the same, or enveloping the same in tin-foil.

From the foregoing statements it will be clear that both a metallic or positive, and a non-metallic or negative resistance, or a combination of both, may be employed as a relay resistance.

The dimensions of the various incandescent resistances capable of being employed in the main circuit and the mode of connecting the same admit of any desired voltage and strength of current being employed in such circuit.

As the tone of a tuning-fork which is barely audible is reinforced by placing the fork on a sounding board, which must be one such that its own tone coincides with that of the tuning-fork, in like manner an electrical sounding board must be provided for the feeble oscillations or interruptions of current of the primary line. Such a sounding-board or resonator is found in the so-called Thomson or Duddell oscillating circuit. Consequently, for the purposes of the present invention the oscillating circuit is of essential importance; it consists of a shunt circuit connected in parallel to the relay resistance and including a variable capacity and a regulatable self-induction device, connected in series with each other.

The whole arrangement then comprises four parts or circuits: I. The line circuit, or means for superimposing current fluctuations. II. The relay circuit, or strong current circuit. III. The Thomson (or Duddell) oscillating or resonating circuit. IV. The telephone or receiving circuit. These four circuits can be coupled so as to be in

operative electrical relation to each other as follows: 1. Magnetically, that is to say, inductively. 2. Electrically, that is to say, with capacity. 3. Galvanically, that is to say, direct metallic connection, wherein all possible combinations between the several circuits are to be taken into consideration. The line current (I) is supplied from the batteries, etc., of the distant station in any one of the customary ways, and therefore does not come into consideration in the present case. The relay or strong current (II) is taken from a central lighting station, an accumulator, or the like, and can be further varied within suitable limits by a regulating resistance. The Thomson or Duddell oscillating or resonating circuit (III) draws its energy from the lamp circuit to which it is coupled or in operative electrical relation, and the less its own resistance the more so does it draw its energy. In the case of the telephone or receiving circuit (IV) an independent source of current is dispensed with and the telephone, according to the way it is coupled up or placed in operative electrical relation to the resonating circuit, is fed either by induced currents (coupling 1), displacement currents (coupling 2), or by partial currents (coupling 3), in which latter case a choking resistance should be placed in the shunt circuit.

Figures 1, 2 and 3 of the accompanying drawings show different improved arrangements with the telephone circuit coupled magnetically, electrically and galvanically, respectively. Figs. 4, 5, 6 and 7, 8, 9, show modifications of the arrangements according to Figs. 1, 2, 3, respectively. Figs. 10 and 11 show further modifications. Fig. 12 shows diagrams hereinafter described.

In the following description and in the drawing the one designation of the relay circuit will be adhered to throughout. This relay circuit consists of the incandescent lamp circuit II and the Thomson oscillating circuit III and in the former 1 denotes an induction coil, Figs. 1, 2, 3, 7, or a simple straight wire, Figs. 4, 5, 6, 8, 9, (omitting the inductive coupling with the line), or an inserted incandescent body, for instance, an evacuated incandescent lamp or a non-evacuated platinum lamp, etc., Figs. 10, 11. In all the figures 2 indicates a regulating resistance such as a slide rheostat or the like, 3 the incandescent body, the wires supplying current to which are wound in solenoid form and thereby produce a bi-polar magnetic field.

4 is the variable condenser, and 5 is the regulatable self-induction coil of the oscillating circuit.

The arrangement and purpose of the components of the line circuit I and of the telephone circuit IV can be readily and clearly determined from the drawings.

The working of the apparatus is as follows: The very weak current fluctuations of the line are impressed upon the relay circuit, and in Fig. 1, are transmitted by magnetic induction from 9 to the circuit 1, 2, 3, of the lamp, the arrangement being such that by means of the very weak alternating currents of the line exactly corresponding alternating tensions are induced in the circuit of the incandescent lamp 3. These alternating tensions are, however, added to and subtracted from that of the original continuous current, whereby a wave current of far higher energy is produced.

Under ordinary conditions only the weak alternating talking current is transmitted by induction by such a wave current, and the energy of the continuous current remains idle or is not utilized. For a very weak alternating current superimposed upon a continuous current is, under ordinary conditions, not able to bring the continuous current into powerful undulation. Now experiments made by the applicant have shown that it is nevertheless possible to bring the continuous current into powerful undulation if a high incandescent resistance be placed in series in the strong current circuit and, parallel thereto, a Thomson oscillating circuit. In the shunt, the current fluctuations are similar but of far greater intensity. For the purpose of preventing the unnecessary and injurious leakage of the incoming alternating talking currents in the network of currents, choking coils should obviously be inserted in the main circuit.

In the arrangement shown in Fig. 2, the working is exactly the same as that of Fig. 1, only in this case the telephone 6 is in electrical operative relation to the resonating circuit by coupling through a capacity.

In Fig. 3 a condenser 7 is placed ahead of the telephone for its protection. The continuous current does not go through the condenser, but the displacement current does. The galvanic or direct metallic coupling might also in this case start from the self-induction coil of the oscillating circuit or from the two coatings of the condenser.

In the arrangement shown in Figs. 4, 5, 6, the working is exactly the same, only the coupling with the secondary line is an electrical capacitative one. It should be noted here, that this coupling might also have taken place with the condenser 4 of the oscillating circuit. The electric capacitative coupling of the telephone is effected by connecting the telephone to two plates of different polarity of a regulatable plate condenser, the plates of which by being displaced relatively to each other enable the amount of the displacement current passing through the telephone to be varied at will, so as to protect the telephone from absorbing an excessive amount of energy.

Figs. 7, 8 and 9 show a galvanic or direct metallic coupling with the primary line, which coupling, with a resistance w placed ahead of it, may take place both across the inductance 1 or a heating spiral (Fig. 7) as well as across the incandescent lamp 3 (Figs. 8 and 9).

Fig. 10 shows a magnetic inductive connection of particularly powerful action. In 10 the relay circuit is placed an incandescent lamp or platinum lamp, instead of the induction coil 1, in which the magnetic field of the incandescent filament, which is wound like a solenoid, is acted upon by a bi-polar 15 electro-magnet 10, 11, with or without an iron core, and the windings of which are traversed by the weak line current fluctuating in rhythm with the speech and with which a condenser 12 may be connected in 20 parallel. The oscillations in the oscillating circuit passing through the coil shaped filament of the lamp 3 produces by induction a varying magnetic field in the electromagnets or windings 13, 14, which strengthened 25 by the condenser 7 are supplied to the telephone 6, said condenser being in parallel or across the circuit between the magnets and telephone. Still simpler is the connection shown in Fig. 11, in which the bi-polar 30 magnetic field of the incandescent filament 1 is influenced at one pole by an electro-magnet 15 traversed by the line current, the other pole of the incandescent filament solenoid acting upon an electro-magnet 16 35 connected to a telephone 6 and with which a condenser may also be connected in parallel. The working is the same as hereinbefore described.

Instead of the electro-magnets with iron 40 cores, simple induction coils, solenoids of cylindrical or conical form may be employed, likewise polarization cells may be substituted for the condensers.

All these arrangements described with 45 reference to the accompanying drawings may however be also used as telegraph relays. In this case the interruption of current coming in from the primary line, produced by the Morse key of the transmitting station, 50 as well as the microphone currents, are transmitted in the manner described above to the main circuit of the telephone relay. If, however, an arrangement according to this invention be employed in an intermediate 55 station, the secondary line is connected up under the same conditions and forms of coupling, instead of the telephone, tapper, or the like.

I claim—

60 1. The combination with a strong relay continuous current circuit, an incandescent resistance in said circuit, a bi-polar magnetic

field to influence said resistance; of means to superimpose current fluctuations on the current in said circuit, a resonating circuit 65 in parallel with the relay circuit, a variable capacity and a regulable resistance in series in the resonating circuit, and a receiving circuit in operative electrical relation to the resonating circuit. 70

2. The combination with a relay continuous current circuit, a resistance therein capable of being magnetically varied and windings in proximity to said resistance, of means to superimpose current fluctuations on said relay circuit, a resonating circuit in parallel with the relay circuit, a variable capacity and regulable resistance in 75 said circuit, and a receiving circuit in operative electrical relation to the resonating 80 circuit.

3. The combination with a relay continuous current circuit having a resistance therein heated by the current in said circuit, means to superimpose line currents on 85 said circuit, an oscillating circuit in parallel with the first circuit and including said resistance, and a third circuit including windings in inductive relation to said resistance. 90

4. The combination with a relay continuous current circuit, a resistance therein capable of being varied by a variable magnetic field and a winding on each side of said resistance to produce a bi-polar magnetic field 95 therefor, of a resistance winding in said circuit, a telephone circuit and means included in said circuit in operative electrical relation to said resistance winding to superimpose the current fluctuations of the talking 100 circuit upon the relay circuit, a resonating circuit in parallel with the relay circuit containing self-inductance and capacity, and a receiving circuit in operative electrical relation to the resonating circuit to receive 105 amplified current variations in synchronism with the talking current variations.

5. The combination with a strong relay continuous current circuit having an incandescent resistance therein; of a resonating circuit having a regulable resistance and a variable capacity therein, an incandescent winding in the relay circuit, a telephone circuit having a winding in magnetic relation to said incandescent winding, and a receiving 110 circuit in operative electrical relation to the resonating circuit. 115

In testimony that I claim the foregoing as my invention, I have signed my name in presence of two subscribing witnesses.

DR. JOSEF SCHIESSLER.
